Frank P. Chernovetz
By his Attorney
George C. Heimrood

UNITED STATES PATENT OFFICE.

FRANK P. CHERNOVETZ, OF BRIDGEPORT, CONNECTICUT.

PADLOCK.

1,411,682.

Specification of Letters Patent. Patented Apr. 4, 1922.

Application filed August 19, 1921. Serial No. 493,710.

To all whom it may concern:

Be it known that I, FRANK P. CHERNOVETZ, a citizen of Russia, residing at Bridgeport, county of Fairfield, and State of Connecticut, have invented certain new and useful Improvements in Padlocks, of which the following is a specification.

This invention relates to improvements in padlocks, and it is the principal object of the invention to provide a padlock with key-operated means for permitting the locking and unlocking of the shackle after a certain operation of said means by a key.

Another object of the invention is the provision of a padlock including means for locking the key-operated means and for automatically unlocking said means during operation of the key.

These and other objects of the invention will be more fully described in the following description reference being taken to the accompanying drawing forming a material part of this disclosure.

In the drawing:

Figure 1 is an end view of a padlock constructed according to the present invention.

Figure 2 is a front view of the padlock, the view being taken along line 2—2 of Figure 1, the cover plate of the lock being partly broken away to illustrate the interior arrangement.

Figure 3 is a longitudinal section through the padlock on line 3—3 of Figure 2.

Figure 4 is a top plan view of a key, and Figure 5 is a section through the key, the section being taken on line 5—5 of Figure 4.

Referring now more particularly to the drawing, the lock 10 has the customary shackle 11 pivoted at one of its ends as at 12 and front cover 13' attached by means of rivets or the like 13.

On a pin 14 secured between the front and rear walls of the casing is pivotally secured a disc 15 provided with teeth at the larger part of its outer periphery and formed with a curved slot 16 near its upper margin by a rim part or flange 17 having an opening 18.

A pin 19 secured to the rear wall of the casing and projecting into the slot 16 limits the rotation of the disc 15 in either direction.

A star wheel 20 is laterally disposed to the disc 15 on a pin 21, and a leaf spring 22, secured at its lower end by a screw 23 to the rear wall of the casing presses the prongs of the star wheel into engagement with the teeth of the disc 15.

A wedge 24 secured by rivets 25 to the front face of the wheel is wider on top and tapering towards its lower end 26 and engages the front of the star wheel 20 to displace the same on its pin 21 against the action of spring 23' wound around the rear part of the pin 21, when the disc 15 is rotated.

This rotation is effected by means of a star wheel 27 pivotally secured on a pin 28 in the casing and engaging with its teeth the teeth on the periphery of disc 15.

A key 29 is provided with a bit 31 adapted to enter the key hole 30 and to engage between the teeth of star wheel 27 to operate the same for operating the disc 15.

A stop 32 is provided in the casing to limit the movement of the bit in one direction.

The lock is operated in the following manner:

Assumed that the shackle 11 is in its locked position shown in Figure 2 in which the rim part 17 of the disc 15 is passed through the same, and the key 29 is inserted with its bit 31 through the key hole 30 and turned by its handle 33 until it engages between the teeth of the star wheel 27 which will be rotated and by its engagement with the teeth of disc 15 will rotate the same, so that its rim part 80 or flange 17 will be gradually drawn out of engagement with the shackle which is released when the end of flange 17 arrives at the opening 18 so that the lock may be opened. During the rotation of the disc 15 90 the wedge 24 will gradually press the star wheel 20 out of engagement with the disc 15 under compression of the spring 23'.

When it is desired to lock the lock again, a rotation of the star wheel 27 in opposite 95 direction will also turn the disc 15 so as to gradually engage with its rim flange the shackle and this rotation of the disc 15 will draw the wedge 24 gradually out of engagement with star wheel 20, which will be gradually pressed forward by spring 23' and engage with its prongs between the teeth of disc 15.

It will be clear that changes may be made in the general arrangement and in the construction of the minor details of my invention without deviating from the spirit and scope of the same.

Having thus described my invention, what I claim is:

1. In a padlock of the class described, a slotted disc, having an open shackle engag-

ing rim flange and teeth upon its outer periphery, a star wheel engaging the teeth of said disc and adapted to be operated by the bit of a key for operating said disc to disengage its flange from the shackle, a second star wheel adapted to engage the teeth of said disc for locking it in the closed position of the lock while said flange and shackle are engaged, and means for allowing a depression of said second star wheel during the operation of said first star wheel by a key.

2. In a padlock of the character described, a toothed disc having a curved facial slot, an open shackle engaging rim flange forming said slot, a pin in said slot limiting the move-

ment of said disc in either direction, a key operated star wheel engaging said disc and adapted to turn the same into and out of the shackle engaging position by its flange, a wedge secured to the face of said disc, a second star wheel, a pin for said last named wheel, a spring on said pin adapted to press the teeth of said second star wheel into engagement with the teeth of said disc but allowing a depression of said second star wheel during the operation of said first named star wheel by a key.

In testimony whereof I have affixed my signature.

FRANK P. CHERNOVETZ.
